US00D973799S

(12) **United States Design Patent** (10) Patent No.: **US D973,799 S**
 Andrews et al. (45) Date of Patent: **** Dec. 27, 2022**

(54) GOLF CLUB HEAD	5,275,412 A	1/1994	Innes
(71) Applicant: PARSONS XTREME GOLF, LLC , Scottsdale, AZ (US)	D350,582 S	9/1994	Miansian et al.
(72) Inventors: Matthew T. Andrews , Scottsdale, AZ (US); Bradley D. Schweigert , Cave Creek, AZ (US); Michael R. Nicolette , Scottsdale, AZ (US)	5,390,919 A	2/1995	Stubbs et al.
(73) Assignee: PARSONS XTREME GOLF, LLC , Scottsdale, AZ (US)	D356,131 S	3/1995	Trimble
(**) Term: 15 Years	D359,330 S	6/1995	Channell
(21) Appl. No.: 29/811,056	D360,444 S	7/1995	Takahashi et al.
(22) Filed: Oct. 11, 2021	5,429,366 A	7/1995	McCabe
(51) LOC (13) Cl. 21-02	D363,101 S	10/1995	Sturm
(52) U.S. Cl. USPC D21/736	D364,665 S	11/1995	Goodrich
(58) Field of Classification Search USPC ..... D21/736-746, 759 CPC A63B 53/00; A63B 53/04; A63B 53/007; A63B 53/065; A63B 53/0487; A63B 60/00; A63B 60/46	D365,864 S	1/1996	Sturm
